(57) **CLAIM**

The ornamental design for a desk light, as shown and described.

DESCRIPTION

FIG. 1 a front, top perspective view of a desk light, showing my new design;

FIG. 2 is a rear, top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and

FIG. 9 is a rear, top perspective view of the desk light with the bulb rotated and the stem slightly folded.

FIG. 10 is a partial enlarged view of portion 10 in FIG. 1; and,

FIG. 11 is a partial enlarged view of portion 11 in FIGS. 1. The dot dash line is included for the purpose of illustrating the bounds of the enlarged view and forms no part of the claimed design.

1 Claim, 11 Drawing Sheets
